US0D1106213S

(12) **United States Design Patent** (10) **Patent No.:** **US D1,106,213 S**
(45) **Date of Patent:** **** Dec. 16, 2025**

(54) **WIRELESS NETWORK CARD**

(71) **Applicant:** **JRD COMMUNICATION (SHENZHEN) LTD.**, Shenzhen (CN)

(72) **Inventors:** **Xiaofeng Xiao**, Guangdong (CN);
Xiaojun Hong, Guangdong (CN);
Kerong Fu, Guangdong (CN); **Yan Zhu**, Guangdong (CN)

(73) **Assignee:** **JRD COMMUNICATION (SHENZHEN) LTD.**, Guangdong (CN)

(**) **Term:** **15 Years**

(21) **Appl. No.:** **35/523,529**

(22) **Filed:** **Nov. 29, 2024**

(80) **Hague Agreement Data**

Int. Filing Date: **Nov. 29, 2024**

Int. Reg. No.: **DM/243047**

Int. Reg. Date: **Nov. 29, 2024**

Int. Reg. Pub. Date: **Jan. 10, 2025**

(30) **Foreign Application Priority Data**

Jul. 4, 2024 (CN) 202430417746.7

(57) **CLAIM**

The ornamental design for a wireless network card, as shown and described.

DESCRIPTION

1. Wireless network card

1.1 : Front

1.2 : Back

1.3 : Left

1.4 : Right

1.5 : Top

1.6 : Bottom

1.7 : Front perspective

1.8 : Back perspective

1.9 : Enlarged view of part A in view 1.1

1.10 : Enlarged view of part B in view 1.2

1.11 : Enlarged view of top view

1.12 : Enlarged view of bottom view

Fig. 1.1 is a front view of the wireless network card showing the new design; Fig. 1.2 is a back view; Fig. 1.3 is a left side view; Fig. 1.4 is a right side view; Fig. 1.5 is a top view; Fig. 1.6 is a bottom view; Fig. 1.7 is a front perspective view; Fig. 1.8 is a back perspective view; Fig. 1.9 is a partial enlarged view of part A; Fig. 1.10 is a partial enlarged view of part B; Fig. 1.11 is an enlarged view of the top view; Fig. 1.12 is an enlarged view of the bottom view.
